UNITED STATES PATENT OFFICE.

WILLIAM R. RAY, OF SAN FRANCISCO, CALIFORNIA.

OIL BURNER.

1,406,413.

Specification of Letters Patent. Patented Feb. 14, 1922.

Application filed April 1, 1919. Serial No. 286,754.

To all whom it may concern:

Be it known that I, WILLIAM R. RAY, a citizen of the United States, residing at the city and county of San Francisco and State of California, have invented new and useful Improvements in Oil Burners, of which the following is a specification.

This invention relates to oil burners, and particularly to improvements on the structure shown and described in my copending application entitled "Oil burner," filed January 15th, 1919, Serial No. 271,287.

One of the objects of the present invention is to provide a turbine driven oil burner of the rotary type in which the oil is ejected and atomized by the combined action of centrifugal force, steam and air, and particularly a mechanism whereby the air employed is induced by an annular steam-actuated nozzle arranged exterior of the oil atomizer.

Another object of the invention is to provide a novel form of bearing member for the support of the centrifugal atomizer and the turbine driving the same, and particularly a packing arrangement for retaining the lubricant employed.

Further objects will hereinafter appear.

The invention consists of the parts and the construction, combination and arrangement of parts as hereinafter more fully described and claimed, having reference to the accompanying drawings, in which—

Fig. 1 is a central, vertical, longitudinal section through the burner.

Fig. 2 is a front view of the burner.

Fig. 3 is a cross section on the line 3—3 of Fig. 1.

Referring to the drawings in detail, A indicates in general a centrifugal atomizer by means of which the oil is centrifugally projected and atomized, 2 an annular air nozzle surrounding the same, 3 a hollow shaft by which the atomizer is carried, 4 a bearing member supporting the hollow shaft and B a turbine by which the shaft and the atomizer carried thereby are driven. While any suitable form of steam or air driven turbine may be employed, I have, in this instance, shown the turbine which consists of a rotor 5 keyed or otherwise secured on the shaft 3. This rotor is enclosed by a housing 6 provided with a permanent head 7 in which is formed an annular steam chest 8. Formed in the inner wall of the steam chest

at a point adjacent the blades 9 of the turbine is a series of angularly disposed nozzle openings 10. These nozzles project the steam at high velocity against the blades of the rotor, thus causing them, together with the shaft supporting the atomizer A, to revolve at high speed, in actual practice, between three and four thousand revolutions, and, in some instances, considerably more.

The steam after impinging on the blades 65 of the rotor passes outwardly into an interior chamber 11 formed within the casing and is then discharged through a suitable outlet, the live or high pressure steam being admitted to the chest 8 through pipe 13. 70

For the purpose of deflecting the steam and throwing it outwardly into the chamber 11 after it has passed through the blades of the rotor, I provide a deflecting disk 14. This deflector may be formed integral with 75 the rotor or otherwise secured thereto. It therefore revolves in unison with the rotor and shaft and the high speed obtained serves the function of centrifugally projecting the steam into the chamber 11, thereby reducing 80 leakage to a minimum and eliminating stuffing boxes of any nature.

The turbine as a whole is here shown as secured to a head member 15 in which is formed a central chamber 16, said head member being in turn secured by means of bolts 17 to the front end of the bearing member 4. The head member 15 serves two functions: first, that of an intermediate spacing member between the turbine and the bearing 85 4 to reduce heat conduction to a minimum, and, secondly, that of a circulating member through which air may be forced to cool the bearing. This is accomplished by securing an annular flange 18 exterior of the head 15 which deflects the air inwardly, as indicated by the arrows. This air enters the chamber 16 through a plurality of radially disposed openings 19 formed in the head, and it is here deflected into the bearing 4 through drilled openings 20 formed in the bearing, which, in turn, communicate with a central cooling chamber 21. The bearing member is provided with two anti-friction ball races 22, one disposed at 105 each end thereof. These ball races or bearings support the hollow shaft 3 and they also serve as a support for the atomizer A and the rotor of the turbine.

Formed within the bearing between the 110

anti-friction bearings 22 is a chamber 23 to which lubricant may be supplied in any suitable manner. This lubricant is retained within the bearing by a pair of packing members 24 and 25. These packing members are secured on the inner end of the bearing 4, and, in reality, consist of nothing more or less than a pair of interspaced caps which are screwed on the end of the bearing, as shown at 26. These caps form a snug fit with relation to the hollow shaft 3 and positively serve the function of retaining the lubricating oil delivered to the bearing and furthermore the function of preventing fuel oil from leaking into the bearing. The bearing constructed and arranged as here shown is at all times kept cool as an ample supply of lubricant is always maintained and air circulation is permitted. The nozzle 2 surrounding the bearing member 4 and the centrifugal atomizing cup A is, in this instance, supported by means of a bracket 27 which may be secured to the frame of the furnace front or the door employed. It is otherwise supported centrally with relation to the bearing 4 by means of a plurality of lugs 28. These lugs are radially disposed and may be cast integral either with the nozzle or the bearing member. The turbine and the bearing members supporting the same may be secured in position by the lugs 28 entirely, or may be further supported by means of a bracket 30 which is secured in a manner similar to the bracket 27. A perfect support and alignment of the different parts employed is thus obtained.

The oil to be atomized and burnt is, in this instance, delivered to the cup by means of a stationary pipe 31. This pipe is screwed into the head 7 of the turbine and supported thereby. Oil is delivered to the pipe from any suitable source of supply, either by gravity flow or under slight pressure, and it discharges into the atomizing cup A through a large slot 32 formed in the forward end of the pipe, this end of the pipe being otherwise closed by means of a cap 33 which is provided with an annular flange 34 to permit an even distribution of the oil delivered to the cup. For the purpose of further atomizing the oil which is centrifugally projected by means of the atomizing cup A, I provide a steam nozzle C. This nozzle is provided with an annular chamber 35 which entirely surrounds the outer end of the nozzle 2. The forward end of this chamber terminates in an annular opening which is considerably inclined when comparing it with the longitudinal axis of the shaft 3. Steam is admitted to the chamber 35 through a pipe 36 and discharges in an annular blast at a point adjacent the discharge end of the atomizing cup. The steam thus discharging serves two functions, first, that of producing

a secondary atomizing effect by further breaking up the oil which is centrifugally projected by the cup, and, secondly, that of inducing an air flow through the nozzle 2. This induction action is produced by the cone-shaped steam blast discharging from the nozzle C. This blast passing directly in front of the atomizing cup and the nozzle 2 produces a sufficient vacuum to induce a strong flow of air through the nozzle. This air mixes with the oil and steam discharging and thereby materially assists in maintaining combustion and in producing a homogeneous combustible mixture before actual combustion takes place.

By referring to Figs. 1 and 3 it will be seen that a considerable number of tubes 38 are arranged in circular formation within the nozzle 2. The annular steam blast discharging from the nozzle directly in front of said tubes induces a flow of air therethrough and it also induces a flow of air through the nozzle 2 under and between the tubes 38. The quantity of air admitted is thus materially increased and the general efficiency accordingly improved.

In actual operation, when handling comparatively low grade crude oils, it is found that a considerable portion of the same has a tendency to crawl or creep over any surface upon which it is deposited. The oil discharging through the pipe 3 will, in actual practice, creep backwardly along this pipe and entirely fill the space between the hollow shaft and the oil supplying pipe. This oil, when cold, has the consistency of tar or heavy asphalt and it therefore has a tendency to secure the hollow shaft against revolving when the burner is cool and first started. This objection is overcome in the present instance, as I provide means for injecting steam between the hollow shaft and the stationary oil supplying pipe. This is accomplished by placing a needle valve 40 which passes directly through the steam chest 8. Steam delivered to the chest 8 when the valve 40 is partly open will therefore escape into a chamber 41 and will here pass between the stationary oil-supplying pipe and the hollow shaft, thus heating this annular passage and at the same time blowing out any oil deposit which may have accumulated.

This valve may also be left partially open during the operation of the burner, as a small amount of steam passing through the end of the passage has a tendency to heat the oil delivering pipe, thereby materially reducing the viscosity of the oil and increasing the flow therethrough. The tendency of any fuel oil to enter the bearing 4 is positively obviated by means of the packing caps 24 and 25, as these maintain a snug fit with the shaft. Any vacuum produced by

the annular nozzle 35 which might have a tendency to draw the lubricating oil out of the bearing 4 is also prevented by the packing caps 24 and 25, as the chambers formed by said caps are in communication with the air cooling passages formed in the bearing and in the head member 15.

By referring to Figs. 1 and 2, it will be seen that the front end of the air nozzle 2 is provided with an annular flange 45 which is considerably larger in diameter than the large end of the air nozzle. This flange is provided for the purpose of preventing the flame produced from being drawn around the air nozzle and entering the forward end thereof. It therefore serves the function of a baffle plate and actual practice has shown that it is of considerable importance, as it positively prevents the flames from licking around the air nozzle and overheating the same. It will also be seen by referring to Fig. 2 that the opening formed in the furnace front through which the burner as a whole is inserted is larger than the flange 45. An annular passage 46 is therefore provided through which air induced by natural draft may be admitted and further support combustion within the chamber.

While a more or less specific design is here shown I wish it understood that this may be varied; similarly that the materials and finish of the several parts employed may be such as the experience and judgment of the manufacturer may dictate.

Having thus described my invention, what I claim and desire to secure by Letters Patent is:

1. An oil burner comprising a centrifugal atomizer, means for delivering fuel thereto, means for rotating the atomizer, an air nozzle surrounding the atomizer, an annular chamber formed in the air nozzle and surrounding the centrifugal atomizer, an annular discharge opening formed in the nozzle adjacent the centrifugal atomizer and communicating with the annular chamber, means for admitting fluid under pressure to the annular chamber, and a plurality of tubes within the air nozzle, said tubes being open at both ends and surrounding the centrifugal atomizer.

2. The combination with a centrifugal atomizer of a hollow shaft supporting the same, a bearing member supporting said shaft, a fluid turbine also supported by said bearing member and adapted to transmit rotary movement to the shaft and the centrifugal atomizer carried thereby, an air nozzle surrounding the centrifugal atomizer, a fluid induction nozzle positioned at the forward end of the air nozzle adapted to induce a flow of air through the nozzle, and a series of open-ended tubes mounted interior of the air nozzle and surrounding the atomizer.

3. The combination with a centrifugal atomizer of a hollow shaft supporting the same, a bearing member supporting said shaft, a fluid turbine also supported by said bearing member and adapted to transmit rotary movement to the shaft and the centrifugal atomizer carried thereby, an air nozzle surrounding the centrifugal atomizer, a fluid induction nozzle positioned at the forward end of the air nozzle adapted to induce a flow of air through the nozzle, a series of open-ended tubes mounted interior of the air nozzle and surrounding the atomizer, means for delivering fuel to the centrifugal atomizer, a pair of packing caps secured on the inner end of the bearing member and surrounding the shaft and passages formed in the bearing member communicating at one end with a chamber formed between said caps and at the opposite end with the atmosphere.

4. An oil burner comprising a centrifugal atomizer, a hollow shaft supporting the same, a stationary pipe extending through said shaft adapted to deliver fuel to the atomizer, a bearing member supporting the hollow shaft, a turbine rotor secured on the shaft and adapted to rotate the same, a housing surrounding the rotor, said housing also forming a support for the stationary fuel delivering pipe, means for admitting fluid under pressure to drive the rotor and means for admitting fluid under pressure into an annular passage formed between the stationary fuel delivering pipe and the hollow shaft.

5. An oil burner comprising a centrifugal atomizer, a hollow shaft supporting the same, a stationary pipe extending through said shaft adapted to deliver fuel to the atomizer, a bearing member supporting the hollow shaft, means for rotating the shaft, means for forcing fluid under pressure between the annular passage formed between the stationary fuel delivering pipe and the hollow shaft, a pair of packing caps secured on the forward end of the bearing member and surrounding the shaft, a pair of annular chambers formed between the caps and the bearing member, and means for forming a communication between said chambers and the atmosphere.

6. An oil burner comprising a centrifugal atomizer, a hollow shaft supporting the same, a stationary pipe extending through said shaft adapted to deliver fuel to the atomizer, a bearing member supporting the hollow shaft, a turbine rotor secured on the shaft and adapted to rotate the same, a housing surrounding the rotor, said housing also forming a support for the stationary fuel delivering pipe, means for admitting fluid under pressure to drive the rotor, means for admitting fluid under pressure into an annular passage formed between the stationary fuel delivering pipe and the hollow shaft, a

pair of packing caps secured on the forward end of the bearing member and surrounding the shaft, a pair of annular chambers formed between the caps and the bearing member, and means for forming a communication between said chambers and the atmosphere.

7. In a burner of the character described the combination with the centrifugal atomizer and the shaft carrying the same, of a bearing member in which the shaft is journaled and a pair of packing caps secured on the forward end of the bearing member, said caps being interspaced to form a pair of annular chambers between the atomizer and the bearing member.

8. In a burner of the character described the combination with the centrifugal atomizer and the shaft carrying the same, of a bearing member in which the shaft is journaled, a pair of packing caps secured on the forward end of the bearing member, said caps being interspaced to form a pair of annular chambers between the atomizer and the bearing member, an inner and an outer annular chamber formed in the bearing member, said inner chamber serving as a lubricating reservoir and the outer as a cool-

ing chamber, and ports formed in the bearing communicating with one of the packing cap chambers, and also with the atmosphere.

9. In a burner of the character described a centrifugal atomizer, a nozzle surrounding the same, a plurality of tubes mounted within the nozzle and surrounding the atomizer, said tubes extending approximately from end to end of the nozzle, and means for inducing a flow of air through the tubes and the nozzles.

10. In a burner of the character described the combination with a hollow shaft and a centrifugal atomizer carried thereby, of a stationary pipe extending through the shaft and adapted to deliver fuel to the atomizer, said pipe having a smaller exterior diameter than the interior diameter of the shaft to form an annular passage between the same, and valve controlled means for admitting a fluid under pressure to said annular passage.

In testimony whereof I have hereunto set my hand in the presence of two subscribing witnesses.

WILLIAM R. RAY.
